UNITED STATES PATENT OFFICE

2,450,023

ELECTRON DISCHARGE DEVICE OF THE
MAGNETRON TYPEPercy L. Spencer, West Newton, Mass., assignor
to Raytheon Manufacturing Company, Newton,
Mass., a corporation of Delaware

Application November 15, 1943, Serial No. 510,423

3 Claims. (Cl. 315—39)

1

This invention relates to a magnetron and more particularly to one which has a plurality of possible oscillating modes, each determined primarily by the geometry of the internal structure. A device of this kind is intended to oscillate in a predetermined principal mode so as to generate a predetermined frequency. Heretofore the existence of additional modes of oscillation has introduced serious difficulties. Particularly when the frequency of a spurious mode was relatively close to but nevertheless different from the frequency of the principal mode, such a spurious mode seriously interfered with the effective and efficient operation of the device.

An object of this invention is substantially to eliminate the undesired character of the additional or spurious modes of oscillation.

Another object is to devise a magnetron structure in which one of the most troublesome spurious modes has its frequency shifted so far from the frequency of the principal mode as substantially to eliminate the undesired character of said spurious mode.

The foregoing and other objects of this invention will be best understood from the following description of an exemplification thereof, reference being had to the accompanying drawing wherein:

Fig. 1 is a transverse section of the magnetron embodying my invention, taken along line 1—1 of Fig. 2; and

Fig. 2 is a longitudinal cross-section taken along line 2—2 of Fig. 1.

The magnetron illustrated in the drawing comprises a combined envelope and anode structure 1 having a central opening therein within which is disposed a cathode structure 2. The envelope is completed by a pair of end rings 3, which together with end caps 4 are soldered in place on the ends of the anode structure 1. The anode structure is formed with a plurality of radially-disposed anode arms 5, each pair of said arms surrounding a loop opening 6. Each circuit comprising each pair of anode arms 5 and the conducting path through the anode structure around each opening 6 contains predetermined values of capacity and inductance, and thus constitutes a tuned circuit which is adapted to oscillate at a predetermined desired frequency. All of said tuned circuits are intended to operate at exactly the same frequency so that all of said circuits contribute to the output of the device when in its oscillating condition.

The cathode 2 is preferably of the indirectly heated thermionic type comprising an outer con-

2

ducting sleeve coated with electron-emissive oxides within which is placed a heating filament, not shown. The heating filament is provided with a pair of end conductors 9 and 10 projecting from opposite ends of the cathode structure. The conducting sleeve of the cathode is connected to one of said end conductors, for example end conductor 9, and is insulated from the other of said end conductors. The cathode structure is supported by a pair of lead-in conductors 8 which pass through a pair of conducting pipes 9 hermetically sealed through the upper and lower end rings 3. Said lead-in conductors are sealed through glass seals 10 carried at the outer ends of said pipes 9.

When a structure such as above described is placed between suitable magnetic poles 11, oscillations are generated which are picked up by a coupling loop 12 inserted in one of the loop openings 6. One end of the coupling loop is connected to the end of a pipe 13 hermetically sealed through the wall of the envelope structure. The other end of said coupling loop is connected to the conductor 14 which passes out through a glass seal 15 carried at the outer end of the pipe 13. As is well known, an additional conducting pipe, not shown, may be connected to the pipe 13 and form with the conductor 14 a concentric transmission line for conducting oscillations generated by the tube to a suitable utilization device.

The desired or principal mode in which the above structure is intended to oscillate is a so-called "transverse" mode. When oscillating in the desired manner, adjacent anode arms 5 are of opposite voltage polarity and oscillating currents flow in the anode structure in a substantially circular path around loop opening 6. As more fully described and claimed in my copending applications, Serial No. 421,145, filed December 1, 1941, now Patent No. 2,417,789, issued March 18, 1947, and Serial No. 465,413, filed November 13, 1942, various undesired spurious modes may be eliminated by interconnecting every other anode arm by a conducting strap at one end of the anode structure and interconnecting the remaining anode arms by a conducting strap at the other end of the anode structure. Therefore I utilize such upper and lower conducting straps 16 in the present structure. In addition to the transverse mode of oscillation described above, the magnetron also tends to oscillate in an undesired "longitudinal" mode, in which the upper and lower ends of each anode arm tend to be of opposite voltage phase. Heretofore in magnetrons of the general configuration, as described above, the natural frequency

of such a longitudinal oscillating mode has been rather close to the frequency of the principal mode. Under these conditions the longitudinal mode has seriously interfered with the effectiveness and efficiency of the device. I have found that if each anode arm is interrupted substantially centrally thereof by an opening 17, the effectiveness and efficiency of the device have been substantially increased. This, I believe, is due to the natural frequency of the undesired longitudinal mode being shifted so far from the frequency of the principal mode as to substantially eliminate the tendency of said longitudinal mode to interfere to any substantial extent with said principal mode.

A convenient way of forming the interruption 17 is to construct the anode 1 of a plurality of laminae 18 and 19, as described and claimed in my copending application, Serial No. 436,891, filed March 30, 1942. Each of these laminae are stamped from a sheet of highly-conducting material, such as copper. Each lamina is shaped so as to define a cross-section of the desired electrode configuration. The laminae 18 are of increased diameter as compared with the laminae 19, thus forming a plurality of external heat-radiating fins. The central lamina, which may be one of the laminae 18, is cut away at its central region to an extent substantially the same as the outer ends of the loop openings 6. In this way the central lamina consists of a simple ring. All of the laminae are stacked and soldered together to form the composite structure. When this is done, it will be noted that each of the anode arms 5 is interrupted substantially along its entire length.

I believe that the beneficial effects which are derived from the above-described structure are due to the following. The frequency of the longitudinal mode has heretofore been determined by the total length of the conducting path which has existed from the top to the bottom of each anode arm. The oscillating circuits thus formed heretofore have had frequencies very close to that of the principal operating mode. By dividing each anode arm 5, as above described, the upper and lower halves of each anode arm are coupled together through the capacity which exists between the juxtaposed surfaces of said upper and lower portions. This capacity being directly interposed into the circuit, which constitutes the longitudinal oscillating circuit, substantially alters the frequency thereof. It no longer is close to the frequency of the principal mode, but is substantially removed therefrom. Whatever the reason for the improved efficiency may be, I have found that magnetrons constructed as above described have operated with substantially increased effectiveness and efficiency.

Of course it is to be understood that this invention is not limited to the particular details as de-

scribed above as many equivalents will suggest themselves to those skilled in the art.

What is claimed is:

1. An electron discharge device comprising a cathode; and an anode structure spaced from said cathode; said anode structure including a pair of arm members which, together with that portion of said anode structure lying therebetween, define a cavity resonator; each of said arm members being centrally slotted in a plane perpendicular to the axis of said cathode, and thereby forming a single pair of capacity-coupled arm elements of equal lengths; all of said arm elements presenting electron-receiving faces of equal lengths to said cathode.
2. An electron discharge device comprising a cathode; and an anode structure spaced from said cathode; said anode structure including a pair of arm members surrounding a loop section and forming therewith a tuned oscillatory circuit; each of said arm members being centrally slotted in a plane perpendicular to the axis of said cathode, and thereby forming a single pair of juxtaposed arm elements of equal lengths the adjacent surfaces of which provide capacity coupling between said arm elements; all of said arm elements presenting electron-receiving faces of equal lengths to said cathode.
3. An electron discharge device comprising a cathode; and an anode structure spaced from said cathode; said anode structure including a pair of arm members surrounding a loop section and forming therewith a tuned oscillatory circuit; said anode structure being formed of a plurality of substantially flat laminae each defining a cross-section of said tuned oscillatory circuit, with the central lamina cut away dividing each of said arm members into a single pair of juxtaposed arm elements of equal lengths; all of said arm elements having electron-receiving faces of equal lengths disposed adjacent said cathode.
